UNITED STATES PATENT OFFICE.

JOHN KRODER, OF NEW YORK, N. Y.

CURTAIN-ROD SUPPORT.

1,077,083.

Specification of Letters Patent.

Patented Oct. 28, 1913.

Application filed June 6, 1913. Serial No. 772,059.

To all whom it may concern:

Be it known that I, JOHN KRODER, a citizen of the United States, and a resident of the city of New York, borough of Manhattan, in the county and State of New York, have invented a new and Improved Curtain-Rod Support, of which the following is a full, clear, and exact description.

The object of the invention is to provide 10 a new and improved curtain rod support or bracket, arranged to permit the manufacturer to conveniently assemble the parts and to allow the user to readily place a curtain rod in position on the support, or to remove 15 it therefrom whenever it is desired to place a curtain on the rod or to remove it therefrom.

In order to accomplish the desired result, use is made of a supporting rod provided at 20 its end with a screw thread and with struck-up lugs in the rear of the screw thread, and a sleeve mounted on the said supporting rod and having a screw thread intermediate its ends and in engagement with the said 25 rod screw thread, to permit of screwing the sleeve lengthwise on the supporting rod, the said sleeve being provided at one end with a terminal stop adapted to abut against the said lugs.

30 A practical embodiment of the invention is represented in the accompanying drawings forming a part of this specification, in which similar characters of reference indicate corresponding parts in all the views.

35 Figure 1 is a perspective view of the curtain rod support with a curtain rod supported thereby; Fig. 2 is a plan view of the same with the sleeve in section and in retracted position; Fig. 3 is a similar view 40 of the same with the sleeve in extended position and supporting one end of the curtain rod; and Fig. 4 is a transverse section of the same on the line 4-4 of Fig. 3.

The supporting rod A is preferably of L 45 shape and is provided at the rear of its transverse member A' with an attaching flange B for fastening the support to a door or window casing by the use of screws, nails, or other fastening devices. The longitudinal member A² of the supporting rod A is provided at its outer end with an external screw thread A³, and immediately in the rear of the said screw thread are lugs A⁴ struck up from the material of the longitudinal member A². A sleeve C engages the

longitudinal member A² and the sleeve is provided intermediate its ends with an external screw thread C' engaging the screw thread A³ so as to permit of screwing the sleeve C lengthwise on the longitudinal member A². The rear end of the sleeve C is provided with a stop C², preferably in the form of an integral flange bent inwardly in the rear of the lugs A⁴ so that when the sleeve C is screwed outward the flange C² finally abuts against the lug A⁴, thus limiting the screwing movement of the sleeve C in this direction.

It will be noticed that the length of the threaded portion A³ and the distance between the thread C' and the flange C² is such that when the sleeve C is screwed outward to its full extent then the screw thread C' is still in engagement with the screw thread A³, and the forward portion of the sleeve C is adapted to receive and support one end of the curtain rod D. In practice, the thread C' has one convolution and is formed by bending a corresponding portion of the sleeve C inward in the form of an internal bead, as will be readily understood by reference to the drawings.

In manufacturing the curtain rod support the tubular sleeve C is without the flange C² to permit of screwing the sleeve 85 C on the threaded portion A³ until the rear end of the sleeve has passed the lugs A⁴, and then the operator by the use of a suitable tool bends the rear end of the sleeve C inward onto the non-threaded portion of 90 the longitudinal member A² to form the stop flange C². In practice two supports such as shown and described are used on a door, window or the like, and arranged opposite each other for supporting the ends 95 of the curtain rod D.

In order to place the curtain rod D in position the operator screws the sleeve C rearwardly into the position shown in Fig. 2, and then places the curtain rod D in 100 position, after which the sleeve C is turned in the opposite direction to screw the sleeve C forwardly into engagement with the corresponding end of the curtain rod D, as illustrated in Figs. 1 and 3.

105 It will be seen that by the arrangement described, the parts forming the support can be readily assembled by the manufacturer and the user can conveniently place the curtain rod D in position on the support 110

or remove it therefrom whenever it is desired to place a curtain on the rod or to remove it therefrom.

Having thus described my invention, I claim as new and desire to secure by Letters Patent:

1. A curtain rod support, comprising a supporting rod provided at its end with an external screw thread and with a struck-up 10 lug adjacent the rear end of the screw thread, and a sleeve for the reception of the end of the curtain rod to be supported, the sleeve being provided between its ends with an internal screw thread screwing on the said 15 exterior screw thread to permit of screwing the sleeve lengthwise on the threaded end of the said supporting rod, the sleeve when screwed in the direction away from the curtain rod having its curtain rod receiving 20 end approximately flush with the terminal of the supporting rod, and the sleeve when screwed in the opposite direction having its receiving end extending beyond the said 25 terminal for engagement with the curtain rod, the said sleeve being provided at one end with a terminal stop adapted to abut against the said lug to limit the screwing movement of the sleeve in one direction.
2. A curtain rod support, comprising a 30 supporting rod provided at its ends with

an external screw thread and with a struck-up lug adjacent the rear end of the screw thread, and a sleeve for the reception of the end of the curtain rod to be supported, the sleeve being provided between its ends with 35 an internal screw thread screwing on the said exterior screw thread to permit of screwing the sleeve lengthwise on the threaded end of the said supporting rod, the sleeve when screwed in the direction away from the 40 curtain rod having its curtain rod receiving end approximately flush with the terminal of the supporting rod, and the sleeve when screwed in the opposite direction having its receiving end extending beyond the said 45 terminal for engagement with the curtain rod, the said sleeve having one end provided with an inwardly-turned flange forming a stop adapted to abut against the said lug to limit the outward movement of the 50 sleeve on the said threaded end of the supporting rod.

In testimony whereof I have signed my name to this specification in the presence of two subscribing witnesses.

JOHN KRODER.
